UNITED STATES PATENT OFFICE.

AUBRY H. MARTIN, OF SHORT HILLS, NEW JERSEY, ASSIGNOR TO RECORDING SPEEDOMETER COMPANY, OF NEWARK, NEW JERSEY, A CORPORATION OF NEW JERSEY.

TAPE-FEEDING MECHANISM FOR RECORDING INSTRUMENTS.

1,017,984.

Specification of Letters Patent.

Patented Feb. 20, 1912.

Application filed April 24, 1911. Serial No. 622,853.

To all whom it may concern:

Be it known that I, AUBRY H. MARTIN, a citizen of the United States, residing at Short Hills, in the county of Essex and State 5 of New Jersey, have invented certain new and useful Improvements in Tape-Feeding Mechanism for Recording Instruments, of which the following is a specification, reference being had therein to the accompanying drawings.

My invention relates to recording instruments, in which it is desired to move past a recording device, a predetermined amount of tape during a certain period of time, or 15 during the operation of some mechanical device, as the revolution of a wheel of a vehicle, and its object is to provide a mechanism for feeding the tape of such instruments which will withstand the vibration 20 and jars to which such instruments are usually subjected, which may be readily adjusted as to the amount of tape to be fed, and which is economical of construction. I attain these objects by the device illustrated 25 in the accompanying drawings, in which similar characters of reference indicate similar parts throughout the various views.

I illustrate and describe my device as adapted to the instrument shown in Letters 30 Patent No. 949,000, granted February 15, 1910, to George S. Maxwell, without limiting myself to such adaptation.

Figure 1 is a perspective view of my invention, Fig. 2 is a plan thereof, and Fig. 35 3 is a plan view of a modification.

1 is the supply case in which the tape 3 is stored in any convenient manner; 4 is a guide-table over which tape 3 passes as it leaves case 1. The take-up roll 2 is mounted 10 on swinging arm 8 at the opposite end of table 4. Upon clockwork mechanism is mounted disk 5, said clockwork being adapted to revolve said disk 5 once every hour. Upon swinging arm 9 is mounted the 15 roller or idler 10, of much smaller diameter than disk 5. The swinging arms 8 and 9 are so arranged with reference to disk 5 that spring 7 may maintain roll 2, roller 10 and disk 5 in operative relation with each other. 20 The arrows indicate the direction of operation. The peripheries of disk 5 and idler 10 are provided with teeth or milled or roughened surfaces, so that they will grip each other and the tape on roll 2. Preferably, I use a knurl in preparing these

peripheries. By changing the diameter of disk 5, it will be understood that the amount of tape to pass a given point on table 4 during one revolution, may be varied.

In the modification shown in Fig. 3, the 60 idler 10 is omitted. The disk 15 operates directly on the tape 13 on roll 12 which is mounted on arm 18, and maintained in operative relation with disk 15 by spring 17. As roll 12 is revolved it pulls tape 13 from case 11 over table 14. By changing the diameter of disk 15 the amount of tape to be fed may be adjusted.

What I claim and desire to secure by Letters Patent is:

1. A speed recorder for recording the movements of a member driven automatically from a vehicle, including a device for feeding tape in predetermined amounts past said member and a clockwork for operating the tape-feeding device, said tape-feeding device consisting of a storage device for the tape, a roll adapted as it revolves to wind the tape thereon, a disk having a circumference equal to the predetermined amount 75 of tape to be fed, and provided on its periphery with a surface adapted to grip the tape, said roll, disk and tape being arranged so that said disk is in contact with said tape only at the point where the peripheries of said roll and said disk are urged together, said disk being driven from the clockwork, and means for maintaining said roll in operative relation to said disk.

2. A speed recorder for recording the 90 movements of a member driven automatically from a vehicle, including a device for feeding tape in predetermined amounts past

95 said member, and a clock-work for operating the tape-feeding device, said tape-feeding device consisting of a storage device for the tape, a roll adapted as it revolves to wind the tape thereon, a disk substantially midway of the width of the tape and having a circumference equal to the predetermined amount of tape to be fed, and provided on its periphery with a surface adapted to grip the tape, said roll, disk and tape, being arranged so that said disk is in contact with said tape only at the point where the peripheries of said roll and said disk are urged together, said disk being driven from the clock-work, and means for maintaining said roll in operative relation to said disk; substantially as described.

3. A speed recorder for recording the movements of a member driven automatically from a vehicle, including a device for feeding tape in predetermined amounts past 5 said member and a clock-work for operating the tape-feeding device, said tape-feeding device consisting of a storage device for said tape, a roll adapted as it revolves to wind the tape thereon, a disk substantially mid- 10 way of the width of the tape and having a circumference equal to the predetermined amount of tape to be fed, an idle roller of smaller diameter than said disk mounted between the roll and said disk, said disk and 15 said idle roller being provided on their peripheries with surfaces adapted to grip each

other, and the tape, said roll, idle roller and tape being arranged so that said idle roller is in contact with said tape only at the point where the peripheries of said roll and said idle roller are urged together, said disk being driven from the clock-work, and means for maintaining said disk, said roll and said idle roller in operative relation with each other; substantially as described.

In testimony whereof, I have hereunto set my hand, this 20th day of April, 1911.

AUBRY H. MARTIN.

In presence of—
H. V. N. PHILIP,
JOHN M. JUDGE.

Correction in Letters Patent No. 1,017,984.

It is hereby certified that the name of the patentee in Letters Patent No. 1,017,984, granted February 20, 1912, for an improvement in "Tape-Feeding Mechanism for Recording Instruments," was erroneously written and printed "Aubry H. Martin," whereas said name should have been written and printed *Aubrey H. Martin*; and that the said Letters Patent should be read with this correction therein that the same may conform to the record of the case in the Patent Office.

Signed and sealed this 2nd day of April, A. D., 1912.

[SEAL.]

C. C. BILLINGS,
Acting Commissioner of Patents.
